UNITED STATES PATENT OFFICE.

CLAUDE R. RICH, OF GRAND RAPIDS, MICHIGAN, ASSIGNOR TO TEESDALE MANUFACTURING COMPANY, OF GRAND RAPIDS, MICHIGAN, A CORPORATION OF MICHIGAN.

LUBRICATING DEVICE.

Application filed April 1, 1925. Serial No. 19,830.

The present invention relates to lubricating devices; and its object is to provide an improved device of that character whereby rotary air pumps and the like may be automatically lubricated economically but nevertheless sufficiently.

This and any other and more specific objects hereinafter appearing are attained by, and the invention finds preferable embodiment in, the structure hereinafter particularly described in the body of this specification and illustrated by the accompanying drawings, in which:—

Figure 1 is a side view of a rotary pump having my lubricating device, certain parts being broken away;

Figure 2 is a front view thereof, partially sectioned on line 2—2 of Figure 1, the face plate being removed;

Figure 3 is a view of certain parts of my device, shown partially sectioned on line 3—3 of Figure 4; and

Figure 4 is a right hand side view of a portion of the same.

In the embodiment of the invention chosen for illustration by the accompanying drawings and for detailed description in the body of this specification, a rotary air pump or "fan" of usual form is shown, having a shaft 1 journalled at 2 in the pump's casing 3 and driven by an electric motor indicated at 4, this shaft carrying vanes 5. The pump's air intake 6, preferably screened at 7, vents into the pump casing at 8, the pump's discharge or exhaust being shown at 9. My device, applied to this pump for lubricating the same, comprises a vessel 10 adjoining the side 11 of the pump's casing and having a closing front plate 12. Lubri-

cating oil is admitted into this vessel 10 from a suitable source through a conduit 13 and a communicating passage 14. A second and much smaller vessel 15 is contained in this vessel 10, and has adjacent its bottom a restricted lubricant inlet 16 (preferably screened at 17) an air inlet 18 adjacent its upper end, supplied by the upwardly extending air pipe 19, and has also an air and lubricant outlet 20, cross-sectionally larger

than the inlet 16 and communicating with the pipe 21 extending first upwardly, and in the construction shown then downwardly, to a vent 22 into the pump's air intake 6 which is cross sectionally larger than this pipe 21.

The operation of this lubricating device is as follows: When the pump is not in operation, oil from the supply pipe 13 running into the vessel 10 may fill it to the level of said pipe and fill the smaller vessel 15 through its inlet 16, and also the pipes 19 and 21 to the same level. When the pump begins to operate, the rapid flow of air through its intake 6 into the pump's casing draws the oil through the pipe 21 commingling the same with the air stream adjacent the vent 8 of the air intake into the pump casing, so that the commingled oil and air in said casing may come into intimate contact with the working parts of the pump 70 therein. After the pump has thus operated for a time, the oil in the small vessel 15 is lowered to nearly the level of the oil and air outlet 20 therefrom, the oil inlet 16 being so restricted that only a small amount of oil 75 may pass therethrough into vessel 15 comparatively with the amount of air and oil which may pass out of the outlet 20 from vessel 15. A stream of commingled oil and air is now drawn through this pipe 21 and 80 is vented into the pump's air intake 6 at said pipe's vent 22. This comparatively small amount of oil, thus drawn into the pump's casing is sufficient to lubricate the pump and is constantly supplied during its 85 operation.

The invention being intended to be pointed out in the claims, is not to be limited to or by details of construction of the particular embodiment thereof illustrated by the 90 drawings or hereinbefore described.

I claim:

1. In a device of the character described: a vessel adapted to contain liquid lubricant and having an air inlet, a lubricant inlet 95 below the air inlet and an upwardly extending air and lubricant outlet between said inlets and cross-sectionally larger than the lubricant inlet; means for drawing air and lubricant outwardly through said outlet; a vessel communicating with said lubricant inlet and adapted to contain the lubricant at a level higher than said air and lubricant outlet.

2. In combination with a rotary air pump 105 having an air intake, a lubricating device comprising: a vessel adapted to contain liquid lubricant and having an air inlet, a lubricant inlet below the air inlet and an air and lubricant outlet between said inlets, 110

cross-sectionally larger than the lubricant inlet and venting into said air intake.

3. In combination with a rotary air pump having an air intake, a lubricating device comprising: a vessel adapted to contain liquid lubricant and having an air inlet, a lubricant inlet below the air inlet and an air and lubricant outlet between said inlets, cross-sectionally larger than the lubricant inlet and smaller than said air intake and venting into said air intake.

4. In combination with a rotary air pump having an air intake, a lubricating device comprising: a vessel adapted to contain liquid lubricant and having an air inlet, a lubricant inlet below the air inlet and an upwardly-extending air and lubricant outlet between said inlets, cross-sectionally

larger than the lubricant inlet and venting into said air intake.

20

5. In combination with a rotary air pump having an air intake, a lubricating device comprising: a vessel adapted to contain liquid lubricant and having an air inlet, a lubricant inlet below the air inlet and an air and lubricant outlet between said inlets, cross-sectionally larger than the lubricant inlet and smaller than said air intake and venting into said air intake; a vessel communicating with said lubricant inlet and adapted to contain the lubricant at a level higher than said air and lubricant outlet.

In testimony whereof I have hereunto set my hand at Grand Rapids, Michigan, this 13th day of March, 1925.

CLAUDE R. RICH.
